UNITED STATES PATENT OFFICE.

ROBERT A. GALLY, OF CINCINNATI, OHIO, ASSIGNOR TO THE BALDWIN COMPANY, OF CINCINNATI, OHIO.

MUSICAL-INSTRUMENT VALVE.

1,269,529.

Specification of Letters Patent. Patented June 11, 1918.

Application filed August 14, 1917. Serial No. 186,225.

To all whom it may concern:

Be it known that I, ROBERT A. GALLY, a citizen of the United States, and residing at Cincinnati, in the county of Hamilton and State of Ohio, have invented certain new and useful Improvements in Musical-Instrument Valves, of which the following is a specification.

Rectangular valves or so called pallets are 10 very old in pipe and reed organs, being used for the control of the ports to the pipes in the slide chest style of pipe organs, or the ordinary type of so called American reed organs, in such uses the valves being ordinarily 15 made of blocks of wood of the full size of such valves and having soft leather facings, or leather facings backed with felt, these valves being lifted from their seats at one end only, or at both ends, and the 20 springs for their return motion being either placed with the two arms of a double arm or pallet spring set with one arm against the wood of such valve or pallet, and the other arm against some other fixed part of 25 the apparatus. When former rectangular valves have been used for the pumbers or bellows they have usually been without any wood or other rigid part moving with the main valve part, the moving valve usually 30 being of a leather sufficiently thick and firm to insure its holding from buckling in at the valve holes under heavy air tension, although in large valves for pipe organ bellows wooden guards are placed over the 35 leather valves, and holding down one line of the leather yet allowing a free part of the leather to move to and from the valve holes under the freely set part of the guard. Circular valves with a rigid reinforcing disk 40 centrally attached to the flexible valve material have been patented by this applicant in his Patent #1,103,754, July 14, 1914.

In the drawings Figure 1, is a plan view of the improved valve applied to a pumber, 45 and Fig. 2 is an end view of the same pumber and valve.

The present shown valve consists of a yielding face piece 1 of leather or the like which is positioned over the ports 2 on the 50 moving board 3 of the pumber of a bellows for a player piano, the particular structure now shown being especially adapted for the high air tension and rapid operation of the pumbers for such instruments which are 55 driven by electric motor or other power

means, as shown in applicant's application #179,414 filed July 9, 1917.

The ports 2 are disposed in a row and the valve face 1 extends over all these ports and sufficiently beyond the end ports and 60 the sides of all the ports to insure a safe sealing against air leakage when said valve is seated. To prevent the buckling of valve face 1 a reinforcing strip 4 of wood or the like is attached lengthwise along the middle 65 of the face 1 on its outer surface, such attaching preferably being made more certain, or done entirely by screws 5 inserted through the face 1 into the stiffener 4. A deadening member 1^a of felt or the like may 70 be inserted between the face 1 and the stiffener 4 to lessen any thump when the valve returns to its seat.

At each end of the stiffener 4 is a slot 6 which slot 6 guides the stiffener 4 to position 75 with the ports 2 by means of the guide pins 7. These guide pins 7 have their upper part bent into an angle hook or dag 8 extending over the stiffener but sufficiently above the said stiffener to allow of the ends of a spring 80 9 extending between the stiffener and the dag 8 and also allow for a proper amount of motion of the valve, the dags 8 acting as checks to said motion, and the extent of such motion can be regulated by making the attached ends of the pins 7 with screw threads where these pins enter the pumber board 3. Such screw threaded attachment of the pins 7 and their dags 8 enable the easy removal of a valve by giving the dag and pin a half 90 turn.

The spring 9 extends a little less than the length between the inner ends of the two slots 5 of the stiffener 4, so that this spring will never rub against either of the pins 7. 95 The middle part of the spring 9 is attached to that part of the stiffener 4, and each end of the spring 9 may be slightly bent or curved upwardly to clear the stiffener and allow motion of the stiffener and the valve, 100 or the stiffener 4 may be coved out or tapered to gain such clearance, or both the bending and the clearing of the stiffener be combined. Deadening felts are preferably employed above and below the end of the 105 spring 9 to avoid any checking noises during the movement of the valve.

To insure greatest possible strength around the edges of the ports 2 and between the said ports, and also gain a free and 110

quiet flow of air through the said ports 2, both the upper and lower entries of these are tapered inward from each face of the pumper board 2 but these tapers preferably 5 not meeting at the middle of the board, but at sufficiently less than that point to leave a moderate distance of a straight hole.

By the present structure a very light, quick acting, quiet, and efficient valve is obtained.

What I claim as my invention is:—

1. In combination: an oblong rectangular valve having a face member and a stiffener member attached to the said face member 15 along the middle and lengthwise of the said face member and on the outer surface of the said face member, said stiffener member being substantially less in width than said face member.
2. In combination: a bodily movable oblong rectangular valve having a face member and a stiffener member attached to the said face member along the middle and lengthwise of the said face member and on 25 the outer surface of the said face member, said stiffener member being substantially less in width than said face member.
3. In combination: an oblong rectangular valve having a face member and a stiffener member attached to the said face member along the middle and lengthwise of the said face member and on the outer surface of the said face member, said stiffener member being substantially less in width than said face 35 member; a spring attached midway the outer face of said stiffener member and free from said stiffener member at the ends of said spring and member, a valve seat, and fixed members attached to the said valve 40 seat and extended to positions opposite the outer ends of the said spring, the said outer ends of said spring standing between the said stiffener and the said fixed members.
4. In combination: a bodily movable oblong rectangular valve having a face member and a stiffener member attached to the said face member along the middle and lengthwise of the said face member and on the outer surface of the said face member, 45 said stiffener member being substantially less 50

in width than said face member, an oblong narrow strip form spring extended in the same general direction as the general direction of the length of the said stiffener and attached midway the outer face of said 55 stiffener member and free from said stiffener member at the ends of said spring and member, a valve seat and fixed members attached to the said valve seat and extended to positions opposite the outer ends of the said 60 spring, the said outer ends of said springs standing between the said stiffener and the said fixed members.

5. In combination: an oblong rectangular valve having a face member and a stiffener member attached to the said face member lengthwise of the said face member and on the outer surface of the said face member, a spring attached midway the outer face of said stiffener member and free from said 65 stiffener member at the ends of said spring and member, a valve seat, and fixed members attached to the said valve seat and extended to positions opposite the outer ends of the said 70 spring, the said outer ends of said spring standing between the said stiffener and the said fixed members.

6. In combination: a bodily movable oblong rectangular valve having a face member and a stiffener member attached to the said face member lengthwise of the said face member and on the outer surface of the said face member, an oblong narrow strip form spring extended in the same general direction as the general direction of the length of the said stiffener and attached midway the outer face of said stiffener member and free from said stiffener member at the ends of said spring and member, a valve seat, and fixed members attached to the said 80 valve seat and extended to positions opposite the outer ends of the said spring, the said outer ends of said springs standing between the said stiffener and the said fixed members.

ROBT. A. GALLY.
